METHOD OF FILLING CONTAINERS AND
APPARATUS THEREFOR

Henry A. Johnson, Kansas City, Mo.

Application April 27, 1946, Serial No. 665,437

3 Claims. (Cl. 226—19)

1

This invention relates to a method of filling collapsible paperboard or cardboard containers and to an apparatus for use in the practice of said method.

More particularly, this invention relates to a method of filling collapsible paperboard or cardboard containers of the character illustrated in my copending application, Serial No. 622,444, filed October 15, 1945, now Patent No. 2,455,124, issued November 30, 1948, on a "Collapsible container."

In my aforesaid copending application I have disclosed a collapsible paperboard container which is particularly adapted for use in holding materials which are poured into an erected collapsible paperboard container in fluid or semi-fluid condition and allowed to cool and solidify. Thus, in my aforesaid application I have disclosed a container which is particularly adapted for holding asphalt which may be poured into the container in hot condition and allowed to solidify and the container then closed and made ready for shipment. However, such collapsible containers are not limited to use with hot materials, such as asphalt, but may be used with other materials such, for example, as ice cream which may be poured thereinto in semi-fluid condition and solidified by freezing.

One of the problems involved in filling collapsible paperboard or cardboard containers with materials poured therein in semi-fluid or fluid condition and allowed to solidify as by cooling from a hot condition, or by freezing, is in preventing the side walls of the collapsible paperboard containers from collapsing or bulging and disrupting the containers as the contents of the containers solidify as aforesaid.

An object of the present invention is to provide a novel method of filling collapsible paperboard or cardboard containers such, for example, as that which forms the subject matter of my above identified copending application as well as other collapsible paperboard or cardboard containers which may be used for the packaging of materials poured thereinto in fluid or semi-fluid condition and allowed to solidify as by cooling or freezing.

An additional object of the invention is to provide a novel method of reinforcing the side walls of the collapsible paperboard containers and holding the containers in proper form during the operation of filling the same and while the contents of such containers are solidifying as by being allowed to cool from a hot condition

2

or by being frozen from a fluid or semi-fluid condition.

An additional object of the present invention is to provide a novel container holding apparatus which may be used in the practice of the new method of filling collapsible paperboard containers.

Other and further objects of the present invention will be apparent from the following description and claims and are illustrated in the accompanying drawings which, by way of illustration, show preferred embodiments of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings,

Fig. 1 is a perspective view illustrating a container holding apparatus which may be used in the practice of the present invention, the container holding apparatus being shown empty and prior to the insertion of the collapsible paperboard or like containers therein;

Fig. 2 is a top plan view of the container holding apparatus shown in Fig. 1 and showing the collapsible paperboard or cardboard containers arranged therein in position to be filled and showing the spacers or separators arranged between the adjacent side walls of the containers;

Fig. 3 is an end elevational view of the container holding apparatus shown in Figs. 1 and 2;

Fig. 4 is a side elevational view of the container holding apparatus shown in Figs. 1, 2 and 3, parts thereof being broken away;

Fig. 5 is a fragmentary side elevational view of the container holding apparatus shown in Fig. 1, showing the containers in filled condition;

Fig. 6 is a fragmentary side elevational view of a modified form of the new container holding apparatus shown in Figs. 1 to 4, inclusive, and showing the collapsible containers arranged thereon in position of use for filling;

Fig. 7 is a fragmentary detail view, partly in section, of one of the latching devices embodied in the apparatus shown in Figs. 1 to 5, inclusive;

Fig. 8 is an elevational view of the latching device shown in Fig. 7;

Fig. 9 is a perspective view of one of the collapsible paperboard containers which may be used in the practice of the present invention;

Fig. 10 is a perspective view of a combination reenforcing and spacing member which may be employed in the practice of the present invention for spacing and reenforcing the end walls of the collapsible paperboard containers which are arranged at the corners of the container-holding apparatus from the end walls thereof;

Fig. 11 is a perspective view of one of the combination reenforcing and spacing members which may be employed in the practice of the present invention for spacing adjacent collapsible paperboard containers and for reenforcing the side walls thereof after the containers have been filled and the contents thereof allowed to solidify; and

Fig. 12 is a perspective view illustrating two rows of collapsible paperboard containers, shown in Fig. 2, arranged in position to be filled, one outside row and one inside row of containers being shown to reveal the arrangement of the corner spacers used in conjunction with the outside rows, and the container-holding apparatus being removed.

Suitable apparatus which may be employed in the practice of the new method of filling collapsible paperboard or cardboard containers is shown in Figs. 1 to 5, inclusive, wherein said apparatus is generally indicated at 10 and includes a rectangular-shaped open supporting base or frame 11 which includes a pair of side rails 32 and a pair of end rails 33. The container-holding apparatus 10 also includes a pair of similar side wall units or gates 12 which are adapted to rest on the side rails 32 of the base frame 11, and a pair of similar end wall units or gates 13 which are adapted to rest on the end rails 33 of the base frame 11. As shown in the drawings, each of the side wall units or gates 12 includes a pair of upright end posts 14 and a plurality of horizontally extending vertically spaced cross rails 15 which may be fastened at their ends in any suitable manner as by nails or screws, to the upright end posts 14. As shown in the drawings, each of the side wall units or gates 12 also includes an intermediate upright post 16 to which the vertically spaced horizontally extending cross rails 15 may be interconnected in any suitable manner.

Similarly, each of the end wall units or gates 13 includes a pair of upright posts 17 and a plurality of vertically spaced horizontally extending cross rails 18 which are connected at their ends in any suitable manner to the vertical posts 17 as by means of nails, screws or the like.

As shown in Figs. 1 and 2 a U-shaped tie member 19 may be loosely placed across the top rails 15 of the side wall units 12 with its ends 34 extending part way downwardly over the sides of the top rails 15 so as to hold the side wall units 12 of the container holding apparatus 10 together and in assembled position during and after the container filling operation.

The container holding apparatus 10 also includes a plurality of latching devices, each of which is generally indicated at 20, and which are shown in detail in Figs. 7 and 8. These latching devices 20 are adapted to maintain the side wall units 12 and the end wall units 13 in assembled relationship and each of the said latching devices 20 includes a relatively stationary latch bar 21 which is attached, as by screws 47, to each of the upright corner posts 17 of the end wall units 13 (Figs. 7 and 8). Each of the relatively stationary latch bars 21 has a latch portion 22 of reduced size (Fig. 7) and each

of the latching devices 20 includes a movable latch member 23 one of which is pivotally mounted, as at 24, upon the upright corner post 14 of each of the side wall units 12. Each of the movable latch members 23 has a notched or indented portion 35 which is engageable with the reduced portion 22 of one of the latch bars 21.

A suitable and typical collapsible paperboard container of the type which may be used in the practice of the present invention is illustrated in Fig. 9 wherein it is generally indicated at 25. The collapsible paperboard container or carton 25 forms the subject matter of my above-identified copending application, and includes side walls 26 and end walls 27, each of the end walls 27 having an attaching flap 38 which is attached, as by staples 39, to one of the side walls 26. Each of the collapsible paperboard containers 25 includes a bottom wall 40 (Fig. 2) and when erected has an open upper end which is adapted to be closed by closure flaps 40 and 41 one of which is attached to each of the side walls 26 and end walls 27, respectively.

The new container holding apparatus includes a plurality of combination reenforcing and spacing members 42 (Figs. 2, 10 and 11) which may be made of any suitable material such, for example, as wood, pressed cardboard or paperboard, light metal or the like. Each of these combination reenforcing and spacing members 42 is generally U-shaped in form and includes an end wall or bight portion 43 and a pair of side walls 44 which may be attached thereto in any suitable manner or formed integral therewith, as desired.

In the practice of the present invention the container holding apparatus 11 shown in Figs. 1 to 5, inclusive, and 7 and 8, may be assembled by arranging the base boards 32 and 33 in a rectangular pattern, as shown, and then arranging the side wall units or gates 12 and the end wall units or gates 13 in upright position upon the base boards 32 and 33, respectively.

The side wall units or gates 12 and the end wall units or gates 13 may then be latched in assembled relationship and held in upright position by pivoting the latch members 23, which are pivotally mounted at 24 on the corner posts 14 of the side wall units or gates 12, into position to engage the notched portions 35 thereof with the reduced portions 22 of the relatively stationary latch bars 21 which are carried by the corner posts 17 of the end wall units or gates 13. The tie bar or member 19 may then be placed over the uppermost horizontally extending rails 15 of the side gates 12 to complete the assembly and thus securely hold the side wall units or gates 12 and the end wall units or gates 13 in assembled relationship and in upright position.

The collapsible paperboard containers, in erected condition, may then be arranged in rows in the thus assembled container holding apparatus in the manner best shown in Figs. 2 and 12. By reference to these figures it will be noted that each two adjacent containers or cartons 25 are separated by a combination spacing and reenforcing member 28 (Fig. 11) which may be made of a sheet of pressed cardboard or other suitable material, arranged between the end walls 27 of each of two adjacent containers 25.

As may also be seen by reference to Figs. 2 and 12 the containers 25 in the several rows thereof are so arranged that the side walls 26 thereof are reenforced by the combination spacing and re-

enforcing members 28 one of which abuts each of the side walls 26 in the inner rows of containers 25 substantially midway between the ends thereof so as to reenforce the side walls 26 of the containers 25 in the inner rows thereof during and after the container filling operation, the side walls 26 of the containers 25 in the outermost rows thereof being reenforced by the horizontal rails 15 of the side wall units or gates 12.

It will also be noted, in this connection, that the end walls 27 of the containers 25 which are spaced or separated by the combination reenforcing and spacing members 28 are also reenforced by these members 28 during and after the container filling operation, the end walls 27 of one of the end containers 25 in each of the outer rows and the end wall 27 of one of the end containers 25 in each of the intermediate rows being reenforced by the horizontal rails 18 of the end wall units or gates 13 (Fig. 2).

As shown in Figs. 2 and 12 one of the combination reenforcing and spacing members 42 is arranged at one end of each of the outside rows of containers 25 and at one end of each of the inside rows of containers 25, the use of one of these combination reenforcing and spacing members being rendered necessary by the arrangement of the containers 25 in the several rows thereof in such a manner that one of the combination reenforcing and spacing members 28 reenforces the side wall 26 of each of the containers 25.

When in position of use the side walls 44 of each of the combination reenforcing and spacing members 42 engage the horizontal rails 18 of one of the end wall units or gates 13 and the end wall or bight portion 43 of each of the members 42 engages and reenforces the end wall 27 of the adjacent container 25 (Fig. 2).

After the collapsible containers 25 and the combination spacing and reenforcing members 28 and 42 have thus been arranged in erected condition and in proper position in the container holding apparatus 10, as shown in Fig. 2, the liquid or semi-liquid material with which the containers 25 are to be filled may be poured thereinto from any suitable source such, for example, as a delivery hose, the outlet end portion or nozzle of which the delivery hose may be successively directed above each of the containers 25 through the open top of the apparatus 10. Thus, for example, a delivery hose adapted to carry hot asphalt from a suitable source, or a delivery apparatus adapted to carry ice cream from a suitable source thereof, may be moved successively from one container 25 to another in order to fill the same. The closure flaps 40 and 41 of the containers 25 may then be moved into closed position and the contents of the containers 25 allowed to solidify therein as by cooling to atmospheric temperature or by freezing. In the latter instance the apparatus may be arranged or moved moved into a freezing or refrigerator room for this purpose.

After the contents of the thus filled containers 25 have solidified the container holding apparatus 10 may be taken apart to facilitate removal of the filled containers 25. This may be accomplished readily by removing the tie rod 19 and pivoting the latch members 23, at 24, into open position whereupon the side wall units or gates 12 and the end wall units or gates 13 may be readily removed from the supporting base 11 of the container holding apparatus 10.

The filled containers 25 with the solidified contents thereof may then be readily transported,

whereupon the process may be repeated by reassembling the container holding apparatus and refilling the same with a new series of the collapsible paperboard or like containers 25, arranged in rows with the combination reenforcing and spacing members 28 and 42 in proper position, as in Fig. 2 and then repeating the filling and solidifying operations.

A slightly modified form of the container holding apparatus is illustrated in Fig. 6 wherein it is generally indicated at 29. This form of the container holding apparatus 10 substantially similar to that which is shown in Figs. 1 to 5, inclusive, and 7 and 8, and those parts thereof which are similar to corresponding parts embodied in the form of the apparatus shown in Figs. 1 to 5, inclusive, and 7 and 8 being given the same reference numerals followed by the additional and distinguishing reference character *a*. However, in the modified form of the invention shown in Fig. 6 the collapsible containers 25a are mounted upon supporting platforms 30 and 46 which are removably arranged within the rectangular supporting base 11a upon upright cross bars 31. The platforms 30 and 46 thus support the collapsible containers 25a above the supporting base 11a so as to permit the step of a portable loading truck to be run under each of the supporting platforms 30 and 46 and thereby lift the selected platforms 30 or 46 and a group of the filled containers 25a for transportation as a unit after the containers 25a have been filled and the container holding apparatus 10a disassembled. This facilitates transporting the filled containers to a refrigerator room or to a shipping platform, or other place. It will thus be seen from the foregoing description, considered in conjunction with the accompanying drawings, that the present invention provides a novel method of filling collapsible paperboard or like containers, and a novel but relatively simple container holding apparatus for use in the practice of the new method and that the invention thus accomplishes its intended objects, and has the desirable advantages and characteristics, including those hereinbefore pointed out and others which are inherent in the invention.

I claim:

1. A method of filling collapsible paperboard containers adapted to be filled with fluid or semi-fluid material to be solidified and each of which said containers include side walls and end walls, a bottom wall, and top closure flaps, said method comprising arranging said containers in erected condition in parallel rows upon a supporting surface with the end walls of adjacent containers in the same row in parallel but spaced relationship and with the side walls of the containers in adjacent rows in contacting relationship so as to reenforce each other and with the top closure flaps of the said containers in open condition, inserting a combination reenforcing and spacing member between the thus spaced parallel end walls of each two adjacent containers in each of the said rows of the said containers and with at least one end portion of each of the said combination reenforcing and spacing members engaging the side wall of one of the containers in the next adjacent row of said containers and approximately midway between the ends of the said side wall, filling the said containers with fluid or semi-fluid material to be solidified therein, and then effecting the solidification of the fluid or semi-fluid contents of the said con-

ainers while thus arranged with the said containers in the position stated.

2. A method of filling collapsible paperboard containers adapted to be filled with fluid or semi-fluid material to be solidified and each of which said containers include side walls and end walls, a bottom wall, and top closure flaps, said method comprising arranging said containers in erected condition in parallel rows upon a supporting surface with the end walls of adjacent containers in the same row in parallel but spaced relationship and with the side walls of the containers in adjacent rows in contacting relationship so as to reinforce each other and with the top closure flaps of the said containers in open condition, inserting a combination reinforcing and spacing member between the thus spaced parallel end walls of each two adjacent containers in each of the said rows of the said containers and with each end portion of each of the said combination reinforcing and spacing members engaging the side wall of one of the containers in the next adjacent row of said containers and approximately midway between the ends of each of the said side walls, filling the said containers with fluid or semi-fluid material to be solidified therein, closing the said closure flaps on the said containers, and then effecting the solidification of the fluid or semi-fluid contents of the said containers while thus arranged with the said containers in the position stated.

3. A collapsible container holding apparatus for use in holding collapsible paperboard or like containers while such containers are filled with fluid or semi-fluid material subsequently solidified therein, said container holding apparatus comprising a substantially rectangular frame including a pair of parallel upright side wall units

and a pair of upright end wall units arranged in parallel relationship and in contacting relationship with the said side wall units at the ends thereof, and a manually operable unit arranged at each corner of the said container holding apparatus for detachably latching one of the said side wall units and one of the said end wall units together in upright and assembled relationship, each of the said side wall units and each of the said end wall units including an upright corner post at each end thereof and a plurality of vertically spaced horizontally extending rails attached at their ends to the said upright corner posts, each of the said manually operable latching units including a relatively stationary latch member attached to and carried by one of the said side wall units, and each of the said manually operable latching units including a manually operable latch member movably mounted on and carried by another of the said side wall units and adapted for latching engagement with the corresponding one of said relatively stationary latch members.
